UNITED STATES PATENT OFFICE.

RICHARD S. BRYANT, OF COLUMBUS, OHIO, ASSIGNOR TO THE BRYANT STEEL WHEEL AND RIM COMPANY, OF COLUMBUS, OHIO.

LOCKING DEVICE FOR TIRE-RETAINING ATTACHMENTS.

No. 841,619.

Specification of Letters Patent.

Patented Jan. 15, 1907.

Original application filed April 28, 1906, Serial No. 314,230. Divided and this application filed July 14, 1906. Serial No. 326,232.

To all whom it may concern:

Be it known that I, RICHARD S. BRYANT, a citizen of the United States, residing at Columbus, in the county of Franklin and State 5 of Ohio, have invented certain new and useful Improvements in Locking Devices for Tire-Retaining Attachments, of which the following is a specification.

My invention relates to improvements in a locking device for tire-retaining attachments, especially of the construction shown in my pending application, Serial No. 270,218, and comprises improved means for preventing the elastic locking-ring from being unseated 15 by severe usage.

It consists, essentially, of a clasp member adapted to be positioned upon a lug extending below the rim-body to engage the locking-ring and to hold the same securely in its 20 normal position against the tire-retaining ring.

The device herein shown is an improved form of the device shown in my pending application, Serial No. 314,230, of which this 25 application is a division.

The accomplishment of the foregoing purposes is achieved by the construction herein-after described and claimed, a preferred embodiment of which is shown in the drawings, in which—

30 Figure 1 is a side view of a portion of the circle of the rim-body, showing the locking device in place. Fig. 2 is a cross-section of the rim-body with the tire-retaining flanges and the locking-ring and locking device in place. Fig. 3 is a side view of a portion of the rim-body with parts in place, the clasp member partly broken away to expose the lug. Fig. 4 is a top view of the ends of the locking-ring. Fig. 5 is a side view of the 35 ends of the locking-ring. Fig. 6 is a modified form of the clasp member adapted to be used with the locking-ring, having its ends cut away as shown in Fig. 7. Fig. 7 is a modification of the locking-ring. Fig. 8 is a vertical section through the rim, showing the clasp member illustrated in Fig. 6 in place.

40 Referring to the accompanying drawings, 1 is the rim-body, adapted for use upon a vehicle-wheel constructed in a well-known manner.

2 is the outwardly-turned flange upon the inner edge of the rim-body.

3 is the inwardly-turned flange upon the outer edge of the rim-body.

4 is a tire-retaining flange which is adapted 55 to be slipped over the rim-body from the outer edge thereof and positioned against flange 2.

5 is a tire-retaining flange adapted to be positioned upon the rim-body on the outer 60 edge of the face thereof after the tire has been placed in position. Tire-retaining flange 5 is adapted to be maintained against outward movement off of the face of the rim-body on account of the pressure of the inflated tire by contacting with the locking-ring 6, which engages the tire-retaining flange 5 at 7. Flange 5 is prevented from moving inwardly by the inflated tire, so that when the tire and flanges have been positioned and the tire inflated the flange 5 is securely held in position against the tire by the locking-ring 6. The locking-ring 6 is split, 70 as shown at 8, and is adapted to be positioned by being sprung inwardly and then permitted to expand into position upon the downturned flange 3, where it is held against outward movement by the engagement of the inner flange 9 with the downturned flange 3.

When in position, the locking-ring 6, which 80 is U-shaped in cross-section, embraces the downturned flange 3 and is held thereon by its own expansion, and when on account of the outward pressure of the inflated tire the outer arm 10 of the locking-ring 6 is engaged 85 by the tire-retaining flange 5 the locking-ring is held from being forced off the rim-body laterally by the engagement of the flange 9 with flange 3.

It is to be understood that the manipulation of the tire-retaining devices herein shown is as follows: Tire-retaining flange 4 is placed upon the rim-body, over the outer edge thereof, and is moved laterally across the face of the rim-body until it engages the 95 flange 2 and is held thereby against pressure adapted to force it off the rim-body. Flange 4 may be brazed or otherwise secured to the rim-body or it may be left detachable. The tire is next positioned upon the rim-body, 100

over the outer edge thereof, and the outer tire-retaining flange 5 is then placed upon the rim-body, over the outer edge thereof, and it is understood that flange 5 is intended 5 to be removable. The locking-ring 6 is then sprung into position over the downturned flange 3, and if the tire be now inflated the expansion thereof will force flange 5 into engagement with the flange or arm 10 on locking-ring 6, which in turn will cause flange or arm 9 on said locking-ring to engage against the inner face of the inwardly-turned flange 3 on the outer edge of the rim-body.

Ordinarily the device thus far described 15 would be sufficient for maintaining a tire permanently in position for use upon the rim-body; but the jarring and jolting due to uneven roadways require additional devices for the purpose of securing the locking-ring 20 firmly in place, and I have therefore provided a locking device which I will now proceed to describe.

My device comprises, essentially, a clasp member 11, formed to be essentially U-shaped in cross-section, the outer arm or flange 12 being preferably longer than the inner arm or flange 13. Through the lower or body portion is provided an opening 14. On the under side of the rim-body, in proximity to the inwardly-turned flange 3 thereof, I provide a lug or bolt 15, extending downwardly from the under face thereof. Preferably a hole is drilled through the rim-body, and the bolt having a flat head is inserted through this opening from the upper face of the rim-body, and the head thereof is made flush with the upper face, and the bolt is secured in place, preferably, by brazing. At its lower end lug 15 is threaded to receive 40 a nut 16. The locking-ring 6 near its ends has its inner flange 9 cut away, as shown at 17 and 18, and when the locking-ring is positioned the ends shown at 17 and 18 abut against the lug, and are thereby held against 45 circumferential movement. The outer flange 10 of the locking-ring 6 has its ends cut slantingly, so that they will overlap, as is apparent in Fig. 3 and Fig. 5. When the parts are properly positioned on the face of 50 the rim-body and the locking-ring has been sprung into place, the clasp member 11 is positioned upon the lug, so that the flange 13 engages the lug upon its inner side, and flange 12 engages the outer face 10 of the 55 locking-ring at the junction of the ends thereof, and when the nut 16 is positioned and turned tightly into engagement with the clasp member the latter is caused to embrace the locking-ring and hold the same 60 securely against displacement.

In Fig. 6 is shown a modified form of the clasp member, (indicated at 27,) which has

its longer flange 28 of triangular shape and adapted when positioned upon the lug to lie between the ends of the locking-ring, which in this construction are made divergent, as shown in Fig. 7. This latter form of clasp member is shown locked in place in Fig. 8. It is understood that the clasp member will be positioned on the lug in the same manner as in Fig. 2; but when the nut is turned against the clasp member the latter will be driven between the ends 19 and 20 and the same will be forced apart and squeezed into secure engagement with the tire-retaining 75 flange and rim-body. The latter construction is neater in its appearance and is equally effective.

The device described herein is simple in its construction and effective in its operation 80 and by its use any tendency of a split self-expansive locking-ring to be unseated from its operative engagement is completely obviated.

What I claim as new, and desire to secure 85 by Letters Patent, is—

1. A locking device for tire-retaining attachments comprising a rim-body, a downturned flange upon the outer edge thereof, a lug depending from said rim-body, a broken locking-ring having inner and outer radial flanges, the inner flange being cut away near the ends thereof whereby said locking-ring is positioned against said lug to prevent circumferential movement, a member adapted to be slipped upon said lug to embrace said locking-ring, and means for securing said member in place whereby the parts are securely locked in position.

2. A locking device for tire-retaining attachments comprising a rim-body, a downturned flange upon the outer edge thereof, a lug depending from said rim-body, a broken locking-ring adapted to be positioned upon said rim-body by self-expansion outwardly, and abutting circumferentially against said lug, a clasp member adapted to be slipped upon said lug to engage said locking-ring, and means for securing said clasp member in place.

3. A locking device for tire-retaining attachments comprising a rim-body, a downturned flange upon the outer edge thereof, a lug depending from said rim-body, a broken locking-ring adapted to be positioned upon said downturned flange by self-expansion outwardly, the ends of said locking-ring being beveled divergently from the upper side thereof, a clasp member adapted to be positioned upon said lug to engage the ends of said locking-ring, and means for securing said clasp member in place, whereby the parts are securely locked in position.

4. A locking device for tire-retaining at-

tachments comprising a rim-body, a down-turned flange upon the outer edge thereof, a lug depending from said rim-body, a broken locking-ring adapted to be positioned upon said downturned flange by self-expansion outwardly, the ends of said locking-ring being arranged to leave an open space between the same, and a clasp member adapted to be positioned upon said lug to enter said open space and engage said locking-ring ends, to

force said ring into engagement with said rim-body, and means to secure said clasp member in place, whereby the parts are locked in position.

In testimony whereof I affix my signature 15
in the presence of two witnesses.

RICHARD S. BRYANT.
